UNITED STATES PATENT OFFICE

117,309

DESIGN FOR A TEXTILE FABRIC

Curt E. Forstmann, Montclair, N. J.

Application October 12, 1938, Serial No. 80,418

Term of patent 3½ years

To all whom it may concern:

Be it known that I, Curt E. Forstmann, a citizen of the United States, residing at Montclair, in the county of Essex and State of New Jersey, have invented a new, original, and ornamental Design for a Textile Fabric, of which the following is a specification, reference being had to the accompanying drawing, forming part thereof.

In the drawing, the sole figure of which is a plan view of a piece of the textile fabric embodying the design of the present invention, the cloth depicted is of a single color.

The characteristic feature of the design consists of parallel stripes repeated in the order comprising a narrow ladder-like stripe and two contiguous stripes, one of which is lighter than the other resulting from the difference in the twist of the yarns employed.

I claim:

The ornamental design for a textile fabric, as shown and described.

CURT E. FORSTMANN.
